STRAND HANDLING APPARATUS

Vaughn L. Johannessen, Cranford, N. J., assignor to Western Electric Company, Incorporated, New York, N. Y., a corporation of New York

Application October 29, 1936, Serial No. 108,155

12 Claims. (Cl. 117—21)

This invention relates to strand handling apparatus and more particularly to an automatic apparatus for maintaining tension in strands on a capstan of a strand working machine upon stoppage of the machine.

An object of the present invention is to provide an efficient and practical apparatus of the character above described.

In accordance with the above object, the invention in one embodiment thereof as applied to strand working machines, for instance, strand twisting machines, in which a plurality of strands pass around a multiple grooved capstan to a point on the machine where they are intertwined, comprises an apparatus wherein the strands are automatically clamped in their individual grooves by a pair of diametrically opposed rollers operated by a dashpot controlled spring in response to a stoppage of the machine, thus preventing slackening of the strands on the capstan and maintaining the proper tension on the strands between the capstan and the point of intertwisting. The rollers are normally spaced from the strands on the capstan when the machine is operating by the energization of a solenoid included in the electrical power circuit of the machine so that when the power circuit is closed, the solenoid rapidly withdraws the clamping rollers from the strands, against the action of the spring, and holds them so until the power circuit is opened whereupon the deenergization of the solenoid permits the spring to move the rollers slowly into clamping relation with the strands.

Other objects and advantages of this invention will more fully appear from the following detailed description, taken in connection with the accompanying drawing, wherein

Fig. 1 is a fragmentary elevational and diagrammatic view, partly in section, of a strand handling apparatus embodying the features of the invention, and

Fig. 2 is a fragmentary plan view thereof.

Referring to the drawing, one embodiment of the invention has been shown which is applicable to the handling of a plurality of parallel strands 10 being drawn over a multiple grooved idler guide sheave 11 from supply sources (not shown) of a strand working or twisting machine by a multiple grooved power driven drawing capstan drum 12, the strands travelling in individual grooves 13 and 14 of the guide sheave and capstan drum 11 and 12, respectively, in the direction of the arrows (Fig. 1). The strands 10 leaving the capstan drum 12 pass through a stationary guide tube 15 where they are bunched and thence between freely

rotatable guide pulleys 16 carried on revolving arms 17 of a twisting machine well known in the art and shown diagrammatically at 18 and driven by a pulley and belt 19 which may be connected to a power source. The machine 18 may include a suitable take-up reel and means to distribute the worked or twisted strands on the reel and a drive therefor (not shown). When the arms 17 carrying the guide pulleys 16 are rotated about the vertical axis of the twisting machine 18 and the capstan drum 12 is drawing the strands 10 from their supplies and delivering them to the revolving pulleys 16, the strands first passing through the stationary guide tube 15, it will be evident that the strands will be intertwined between the tube and the pulleys, the twisted strands being taken up under tension on the reel (not shown). Methods of driving a take-up reel through a friction clutch or the like for applying a constant tension to the strand being wound are common in the art and it is believed unnecessary to illustrate this mechanism. It also is old to mount a take-up reel in a frame which is rotated about the axis of a group of strands being twisted, as illustrated in the patent to Bouget et al. 2,041,812, May 26, 1936.

Although the strands as they are withdrawn from the supply sources are subjected to some tension by means of a tension regulating brake associated with each supply source, there may be some slackening of tension between the supply and the capstan when the machine is stopped. To prevent slackening or loosening of the strands 10 in their individual capstan drum grooves 14, which would result in a disturbance of the intertwist in the strands between the guide tube 15 and the pulleys 16 due to a lessened tension in the strands between the capstan drum 12 and the point of intertwisting upon stoppage of the twisting machine, particularly since the lessened tension would often be non-proportionate among the individual strands, the following described strand handling or tension control mechanism is provided:

Integral with a base 20 is a hollow frame or standard 21 on which is journaled a horizontal shaft 22, the shaft having fixed thereto within the standard a sprocket wheel 23 which is driven in the direction of the arrow from a suitable source of power (not shown) by a chain 24. Pinned to the forward end of the shaft 22 is the multiple grooved capstan drum 12 formed with a plurality, in the present embodiment, four peripheral grooves 14, one for each strand 10. The idler guide sheave 11 is likewise provided with

four grooves 13, one for each strand. Disposed diametrically opposite to each other about the axis of the capstan drum are pivotal arms 25 fixed to shafts 26 journaled on the standard 21. 5

5 Freely journaled on the outer end of each of the arms 25 is a roller 27 which is aligned with the grooved periphery of the capstan drum 12 and of such dimensions that when moved toward the capstan drum its peripheral surface will engage 10 each of the strands 10 on the capstan drum. The rollers 27 are freely journaled on the arms 27 so that in case the rollers engage the strands 10 before the capstan drum 12 has stopped or they are not withdrawn before the capstan drum 15 starts to rotate, the rollers will rotate freely without deleterious effect on the strands. The rollers 27 are faced on their peripheries with a suitable anti-slipping material, such as rubber, to effect a firm grip on the strands 10 when engaged 20 therewith and also to prevent marring the strands or their covering.

Upon the end of the shaft 22 opposite to the capstan drum 12 is pivotally carried a lever 28 which is operatively connected to arms 29 fixed 25 to the shafts 26, which also carry the arms 25, by links 30, each link at one end being pivotally connected to the lever 28 the same distance from its pivotal axis, the opposite ends of the links being pivotally connected to the outer ends of 30 the arms 25. Thus, it will be apparent that the rollers 27 will be moved in unison toward and from the strands 10 on the capstan drum 12 when the lever 28 is rocked counterclockwise and clockwise, respectively, about the shaft 22, the 35 movements of the lever 28 being transmitted to the rollers by means of the links 30 and arms 29 and 25. The outer end of the long arm of the lever 28, as indicated at 33, is pivotally connected to the upper end of a tube 34 projecting 40 from a dashpot 35 which comprises a cylinder and a piston 36 therein which is connected to the lower end of the tube 34. A compression spring 37 below the piston tends to move the piston and tube upwardly to rock counterclockwise the lever 28 and through the links 30 and arms 29 and 25 causing the rollers 27 to be drawn simultaneously into clamping engagement with the strands 10 on the capstan drum 12.

For controlling the rate of speed at which the 50 rollers 27 move into engagement with the strands 10 on the capstan drum 12 when the spring 37 is permitted to act, an adjustable oil valve 40 is included in the dashpot 35 for regulating the escape of oil from the upper side of the piston 36 to the lower side thereof during the expansion of the spring in a manner to be presently described. By adjusting the valve 40, which is carried in the tube 34 and screw threadedly connected thereto at its upper end, the escape of oil 55 from the upper side of the piston 36 to the lower side thereof may be regulated and thereby the rate of speed at which the piston moves upwardly which, by means of the tube 34, lever 28, links 30, and arms 29 and 25, controls the movement 60 of the rollers 27 into clamping engagement with the strands 10.

Also pivotally connected to the long arm of the lever 28 at a point between the adjacent link 30 and the dashpot tube 34, is the upper end 70 of a link 41, the lower end thereof being similarly connected to a core 42 of an electrical solenoid 43. The solenoid 43 is included in the electrical power circuit for the machine which is driven by an electric motor and when the motor circuit is closed to set the machine in motion, 75

the circuit through the solenoid is also closed. The capstan, twister and take-up may be driven by a single motor with interconnecting gearing or by separate motors. In the latter case, it will be understood that electric power is applied to 5 and disconnected from the motors simultaneously.

In the operation of the above described strand handling apparatus starting with the strand working or twisting machine 18 in a non-operating condition wherein the strand gripping rollers 27 are engaged with the strands 10, as shown in the drawing, the machine is set in motion by closing the circuit to the driving motor or motors. Simultaneously therewith, the solenoid 43, 15 which is included in the motor circuit, is energized and the core 42 is rapidly drawn downwardly and the lever 28 connected thereto is rocked clockwise about the shaft 22 and through the described connections to the rollers 27, the 20 latter are quickly withdrawn from clamping engagement with the strands 10 on the capstan drum 12.

To permit a quick displacement of oil from the lower side of the piston 36 to the upper side 25 thereof when the core 42 and thereby the piston 36 is drawn rapidly downwardly, a check valve is provided in the dashpot 35 comprising a free or floating washer 45 surrounding the tube 34 above the piston 36 which is perforated. In 30 the downward movement of the piston 36, the oil therebelow is forced through the perforations in the piston, the washer 45 being lifted from the piston. During an upward movement of the piston 36, the washer 45 serves to close the perforations in the piston to the passage of oil from above the piston, the valve 40 at this time controlling the passage of oil.

By means of the pivotal connection 33 between the lever 28 and the dashpot tube 34, the dashpot spring 37 is compressed during the rocking of the lever. During the operation of the machine, the strands 10 are drawn by the capstan drum 12 from their supply sources (not shown) at the left of the idler guide sheave 11, over the latter and around the capstan drum and delivered to the twisting machine 18, each of the strands travelling in its respective grooves 13 and 14 of the idler guide sheave and capstan drum 12, respectively. As long as the machine 18 is operating, 50 the rollers 27 are disengaged from the strands 10 and the dashpot spring 37 will be held compressed. When the machine is stopped by opening the motor circuit, the circuit through the solenoid 43 will likewise be opened and the deenergization 55 thereof releases the energy stored in the compressed dashpot spring 37 with the result that the lever 28 is rocked counterclockwise and the rollers 27 are moved slowly into clamping engagement with the strands 10, the speed at which the rollers 60 move being determined by the adjustment of the dashpot valve 40 in the manner previously described. Preferably, the rollers 27 should firmly engage and grip the strands 10 in their individual capstan drum grooves 14 at substantially the 65 moment the capstan drum 12 comes to a halt, thus maintaining the proper operating tension in the strands extending around the capstan drum 12 to their points of being worked or intertwined in spite of slackened tension in the 70 strands between the capstan drum and the strand supply sources.

From the above description of the apparatus for controlling tension in strands on a capstan of a strand working or twisting machine upon stop- 75

page of the machine, it will be readily seen that the strands are automatically maintained under suitable tension in the capstan grooves at all times, even though the tension on the strands 5 between the capstan drum and the strand supply sources is slackened when the machine stops, with the result that no disturbance of the intertwist in the strands between the capstan drum and the point of intertwisting will occur when the 10 machine is stopped.

Although the invention herein described and illustrated is particularly well adapted for use in strand twisting machines, it will be understood that the invention is capable of many other modifications and applications and is to be limited 15 only by the scope of the appended claims.

What is claimed is:

1. In strand handling apparatus, a take-up means, a capstan for receiving strand material 20 and delivering it to said take-up means, and means responsive to a stoppage of the take-up means and the capstan for maintaining the tension on the length of strand between the capstan and take-up means.

25 2. In strand handling apparatus, a common capstan for receiving a plurality of strands, a common take-up means for taking up strands under tension from said capstan, means for simultaneously clamping said strands, and means actuating automatically when the apparatus is stopped to actuate said clamping means for maintaining a predetermined tension on the strand portions entering the take-up means.

3. In a strand twisting apparatus, a take-up means for twisted strands, means for twisting strands together, a capstan for receiving strands and delivering them to said twisting means, and means responsive to the stoppage of said take-up 35 means and capstan for maintaining the tension on the lengths of strands between the capstan and take-up means.

4. In a strand handling apparatus, a capstan having a plurality of grooves for receiving separate strands, means for driving said capstan to 45 advance said strands, and movably mounted normally ineffective means effective when the capstan is stopped for clamping the strands in said grooves.

5. In a strand handling apparatus, a capstan, 50 means for supplying strand material to said capstan, means taking up the material under tension from the capstan, and means for clamping the material when the capstan is stopped, said means comprising a clamping element, a solenoid for 55 moving said element in one direction, a spring for moving it in the other direction, and means for retarding one of said movements.

6. In a strand twisting apparatus, a capstan, means for supplying a plurality of strands to said 60 capstan, means for intertwisting strands advanced by said capstan from said supply means, means for driving said capstan and twisting means, and movably mounted normally ineffective means effective when the capstan and twisting 65 means are stopped for clamping the strands to said capstan to prevent slackness of the strands thereon and thereby preventing disturbance of the twists in the strands.

7. In a strand handling apparatus, a capstan 70 having a plurality of grooves for receiving separate strands, means for driving said capstan to advance said strands, and means for clamping the strands in said grooves when the capstan is stopped, said means comprising interconnected

rollers arranged about the periphery of the capstan and movable in unison into and out of clamping engagement with the strands thereon, a solenoid for moving said rollers in one direction, and a dashpot for moving them in the other direction. 5

8. In a strand handling apparatus including means for working a strand and a capstan for moving the strand to said working means, means for rotating the capstan and driving said working 10 means including electric motive means and an operating circuit for said motive means, and means including a movably mounted element responsive to the opening of said circuit when stopping said capstan and working means to cause 15 said element to clamp the strand to the capstan for maintaining the tension on the length of strand between the capstan and working means.

9. In a strand handling apparatus including 20 means for working a strand and a capstan for moving the strand to said working means, means for rotating the capstan and driving said working means including electric motive means and an operating circuit for said motive means, means mounted for movement relative to said capstan 25 for clamping the strand thereto, and means for moving said latter means into clamping engagement with the strand on said capstan in response to the opening of said circuit when stopping said capstan and working means for maintaining the 30 tension on the length of strand between the capstan and working means.

10. In a strand handling apparatus including 35 means for working a strand and a capstan for moving the strand to said working means, means for rotating the capstan and driving said working means including electric motive means and an operating circuit for said motive means, and means responsive to the opening and closing of 40 said circuit when stopping and starting said capstan and working means to clamp the strand to said capstan for maintaining the tension on the length of strand between the capstan and working means upon stoppage thereof and for unclamping the strand when the capstan and 45 working means are started when the circuit is closed.

11. In a strand handling apparatus, including 50 means for working a strand and a capstan for moving the strand to said working means, means for rotating the capstan and driving said working means including electric motive means and an operating circuit for said motive means, means 55 movable to and from the strand on said capstan for clamping and unclamping the strand to the capstan, and means including an electric solenoid in said circuit responsive to the closing and opening of the circuit when starting and stopping said capstan and working means to move the 60 clamping means from the strand upon starting the capstan and working means and moving the clamping means to clamp the strand to the capstan when the capstan and working means are stopped for maintaining the tension on the length 65 of strand between the capstan and working means.

12. A device for clamping strand material against a capstan, comprising a movable support, a roller freely journaled on said support on an axis parallel to the axis of the capstan, and 70 means for moving the support to bring the roller into engagement with the strand material.
